UNITED STATES PATENT OFFICE.

WILLIAM PETER GELABERT AND THOMAS GRENVILL NELSON, OF SWEETSPRINGS, MISSOURI.

DESIGN FOR A BUCKLE.

SPECIFICATION forming part of Design No. 34,368, dated April 16, 1901.

Application filed March 11, 1901. Serial No. 50,768. Term of patent 14 years.

To all whom it may concern:

Be it known that we, WILLIAM PETER GELABERT and THOMAS GRENVILL NELSON, citizens of the United States, residing at Sweet-
5 springs, in the county of Saline and State of Missouri, have invented and produced a new and original Design for a Buckle; and we do hereby declare the following to be a full, clear, and exact description of the same, reference
10 being had to the accompanying drawings, forming a part thereof.

This invention relates to a new and original design for a buckle; and it consists of a shape and configuration as shown in the accompanying drawings and hereinafter described.

15 In the drawings, Figure 1 is a side elevation, and Fig. 2 is a plan view.

A A' designate the sides of the buckle, connected by the transverse bars B c c' B'.

C designates the tongue.

The parts a a' of the sides A A' extend upward and the parts b b' downward in the opposite direction.

The essential features of the design are the parts a a' and b b' of the frame and the trans- 25
verse bars c c'.

Having thus described the invention, what is claimed as new, and desired to be secured by Letters Patent, is—

The design for a buckle, substantially as 30
shown and described.

In testimony whereof we affix our signatures in presence of two witnesses.

WILLIAM PETER GELABERT.
THOMAS GRENVILL NELSON.
